(57) **CLAIM**

The ornamental design for a display station and a three-dimensional display ceiling, as shown and described.

DESCRIPTION

FIG. 1 is a front perspective view of a display station showing our new design;

FIG. 2 is a front elevational view of the display station of FIG. 1;

FIG. 3 is a left side elevational view of the display station of FIG. 1, the right side elevational view being a mirror image thereof;

FIG. 4 is a rear elevational view of the display station of FIG. 1;

FIG. 5 is a bottom plan view of the display station of FIG. 1; however, the bottommost surface of the display station does not form part of the claimed invention;

FIG. 6 is a top plan view of the display station of FIG. 1; FIG. 7 is a right side sectional view taken along the line 7—7 of FIG. 2 to further show the interior of the display station of FIG. 1;

FIG. 8 is a right side sectional view of a three-dimensional display ceiling showing our new design, wherein exemplary projected optics that may be projected on the three-dimensional display ceiling are indicated by dashed arrows; and, FIG. 9 is a bottom plan view of the three-dimensional display ceiling of FIG. 8.

The broken lines in the drawings are provided to illustrate the environment of the claimed invention and do not form a part of the claimed invention. The internal portions of the display station illustrated with cross-sectional hatching in the drawings also do not form a part of the claimed invention.
